COMBINATION LEATHER AND RUBBER HEEL

Michele Leopaldi, New York, N. Y.

Application June 25, 1948, Serial No. 35,270

5 Claims. (Cl. 36—35)

1

This invention relates to new and useful improvements in a combination leather and rubber heel, and is a substitute for my abandoned application Serial No. 435,012 filed March 17, 1942.

More specifically, the invention proposes the construction of a combination leather and rubber heel having a body portion constructed of cork, leather or other similar material, and which is provided with a rubber insert at its rear outer side or point of greatest wear in a manner to form a heel having the wearing qualities of an all rubber heel without requiring the quantity of rubber now used in producing a common all rubber heel.

Another object of this invention proposes the provision of a rigid plate mounted in the rubber insert at its point of greatest wear in a manner to materially increase the normal wearing life of this insert.

A further object of this invention proposes disposing the rigid plate within an opening extended inwards from the bottom face of the insert and engaging a nail through the rigid plate in a manner to securely lock the rigid plate in position in the opening.

Still another object of this invention proposes an auxiliary means for assisting the nail in retaining the rigid plate in position within the opening in a manner to securely lock the rigid plate in position and prevent it from dropping out of the opening.

It is a further object of the present invention to construct a shoe heel which is simple and durable, easily attached to a shoe and which may be manufactured and sold at a reasonable cost.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a partial bottom plan view of a shoe having a combination leather and rubber heel constructed in accordance with this invention.

Fig. 2 is a vertical sectional view on the line 2—2 of Fig. 1.

Fig. 3 is still another view similar to Fig. 1, but illustrating another modification of the invention.

Fig. 4 is a vertical sectional view on the line 4—4 of Fig. 3.

2

Fig. 5 is a vertical sectional view on the line 5—5 of Fig. 3.

Fig. 6 is an enlarged view of a portion of Fig. 4 before the insertion of the nail.

Fig. 7 is a similar view to Fig. 4, but illustrating another modification of the invention.

The combination of leather and rubber heel, according to this invention, is to be applied to a conventional shoe 10 and includes a body portion 11. This body portion 11 is built up of a plurality of superimposed layers of cork, leather or other similar material and is securely attached to the base 12 of the heel portion of the shoe 10.

A U-shaped insert of rubber 13 engages completely about the back and side edges of the body portion 11. This insert of rubber is retained in position by means of nails 14 passed through openings in the insert 13 and engaged into the base 12.

At a point between the back and outer side of the insert 13, or its point of greatest wear, it is formed with an inwardly extending recess 15 within which a rigid plate 16 is mounted. This plate 16 is of non-circular shape, preferably substantially triangular, in horizontal cross section and is disposed slightly inwards from the peripheral edge of the insert 13 and is formed of composition, metal or other similar material having unusual strength and long wearing qualities. The plate 16 is retained in position within the recess 15 by means of a nail 17 which passes through aligned openings in the plate 16 and the insert 13 and engages the base 12.

Adjacent the plate 16, the body portion 11 of the heel has an undercut portion, and the insert 13 is formed with a projection 18 which extends into this undercut area. This projection 18 tends to thicken the rubber insert 13 at its point of greatest wear and prevent the insert from breaking into two parts as this area becomes worn away.

It is believed that the manner of attaching the combination leather and rubber heel to the heel portion of the shoe 10 will be obvious to those skilled in the art.

The form of the invention illustrated in Figs. 3 to 6 is similar to that previously described except for the provision of a means for assisting the nail 17 in holding the rigid plate 16 in position within the recess 15.

This means is characterized by a sleeve 20 which concentrically engages the nail 17. The sleeve 20 is formed at its inner end with a flange 21 of any suitable size. The flange 21 is in intimate contact with the adjacent face of the plate 16 and has the contour of the recess 15.

The outer end of the sleeve 20 is enlarged at 22 and engages about the head of the nail 17. Slits 23 are extended inwards from the outer end of the sleeve 20 and permits the walls of the sleeve to be compressed as shown in Fig. 6, which is the normal position of the sleeve before the insertion of the nail 17.

In assembling the heel, the rigid plate 16 together with the sleeve 20 is inserted into the recess 15 and a convenient turning tool is engaged into the free end of the slits 23 and used to turn the sleeve 20 relative to the plate 16. The peripheral edges of the flange 21 are sharpened and as the sleeve 20 is turned relative to the plate 16 the edges of the flange 21 will cut into the rubber insert 13 and hold the plate 16 in position. The nail 17 is then forced through the sleeve 20 to engage into the base 12. As the nail 17 is forced through the sleeve 20, the sleeve will be spread from the position shown in Fig. 6 to the position shown in Figs. 4 and 5. The walls of the sleeve 20 will then frictionally engage the shank portion of the nail 17 and maintain the sleeve against turning from the position in which the edge portions of the flange 21 engage into the rubber insert 13. In other respects this form of the invention is similar to that shown in Fig. 1 and like letters of reference are used to identify like parts in each of the several views.

In Fig. 7 the insert 13 is shown with a vertical edge 18^a instead of the projection 18. In other respects, this form of the invention is similar to the form shown in Figs. 4 to 6.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. A heel for a shoe, comprising a body portion of leather, an insert of rubber, and a rigid plate set into said rubber insert at its point of greatest wear, and means for holding said plate in position within a recess formed in said insert, comprising a rotative sleeve extended through an opening formed in said plate and having a flange with sharpened edges which cut into said rubber insert, and a nail engaged through said sleeve for holding said sleeve against turning.

2. In a heel having a body portion with an insert in the body portion formed with a recess in which a rigid plate is positioned, means for holding said rigid plate in position within said recess, said rigid plate being of triangular shape in cross-section and said recess being conformed to the shape of said rigid plate, said holding means comprises a sleeve rotatively extended through said rigid insert, a flange formed on the inner end of said sleeve and conformed to the shape of said rigid plate, said flange having its edges sharpened to cut into said rubber insert when said sleeve is turned, means facilitating turning of said sleeve to engage the sharpened edges of said flange with the material of said rubber insert, and means for securing said sleeve against accidental rotation.

3. In a heel having a body portion with an insert in the body portion formed with a recess in which a rigid plate is positioned, means for

holding said rigid plate in position within said recess, said rigid plate being of triangular shape in cross-section and said recess being conformed to the shape of said rigid plate, said holding means comprises a sleeve rotatively extended through said rigid insert, a flange formed on the inner end of said sleeve and conformed to the shape of said rigid plate, said flange having its edges sharpened to cut into said rubber insert when said sleeve is turned, means facilitating turning of said sleeve to engage the sharpened edges of said flange with the material of said rubber insert, and means for securing said sleeve against accidental rotation, said sleeve having its outer end slit to be engaged by a turning tool to form the said means facilitating turning of said sleeve.

4. In a heel having a body portion with an insert in the body portion formed with a recess in which a rigid plate is positioned, means for holding said rigid plate in position within said recess, said rigid plate being of triangular shape in cross-section and said recess being conformed to the shape of said rigid plate, said holding means comprises a sleeve rotatively extended through said rigid insert, a flange formed on the inner end of said sleeve and conformed to the shape of said rigid plate, said flange having its edges sharpened to cut into said rubber insert when said sleeve is turned, means facilitating turning of said sleeve to engage the sharpened edges of said flange with the material of said rubber insert, and means for securing said sleeve against accidental rotation, said sleeve having its outer end slit to be engaged by a turning tool to form the said means facilitating turning of said sleeve.

5. In a heel having a body portion with an insert in the body portion formed with a recess in which a rigid plate is positioned, means for

holding said rigid plate in position within said recess, said rigid plate being of triangular shape in cross-section and said recess being conformed to the shape of said rigid plate, said holding means comprises a sleeve rotatively extended through said rigid insert, a flange formed on the inner end of said sleeve and conformed to the shape of said rigid plate, said flange having its edges sharpened to cut into said rubber insert when said sleeve is turned, means facilitating turning of said sleeve to engage the sharpened edges of said flange with the material of said rubber insert, and means for securing said sleeve against accidental rotation, said sleeve having its outer end slit to be engaged by a turning tool to form the said means facilitating turning of said sleeve.

6. In a heel having a body portion with an insert in the body portion formed with a recess in which a rigid plate is positioned, means for
